TOBACCO PIPE

Joseph Pedery, New York, N. Y.

Application February 9, 1934, Serial No. 710,455

2 Claims. (Cl. 131—205)

This invention relates to improvements in tobacco pipes. The draught or suction of such pipes is frequently impaired through the clogging which takes place at the bottom of the pipe bowl, and particularly at the junction of the bowl and the pipe stem, which clogging is due to continual accumulation of various ingredients distilled out of the tobacco during the smoking. Those accumulated ingredients have to be frequently scraped out of the bowl, as, besides impairment of the suction, they also form hard or viscous masses which seriously vitiate the taste of the tobacco.

The principal object of the invention is to provide a tobacco pipe with improved and efficient means for remedying the above mentioned disadvantages, to ease the conveyance of the smoke through the pipe, and to prevent the distilled objectionable ingredients of the tobacco from reaching the smoker's mouth.

Another object is to provide a tobacco pipe having simplified, inexpensive, reliable, efficient, and improved means for retaining an absorbent material for remedying said disadvantages, and for readily, rapidly, and conveniently discarding and renewing said material.

A further object is to effect the improved distillation of objectionable ingredients from the tobacco within the pipe.

A still further object is to provide improved means for gaining access to all the parts and surfaces in the region of the junction of the pipe bowl and stem, for the rapid, convenient, and efficient cleaning of the same.

Other objects and advantages will hereinafter appear.

The accompanying drawing is a longitudinal cross-sectional elevation of a tobacco pipe embodying the above referred improvements.

The pipe 1 comprises a bowl 2 and stem 3, and at the centre of the bottom of the bowl is located a fitting 4 comprising a floor 5 having a central, upwardly extending, frusto-conical projection 6, and an upstanding annular wall 7 which projects upwardly from the margin of floor 5 and surrounds the conical projection 6. The fitting 4 is secured in place by being wedged within the bowl 2 in the manner shown, and is provided with a bore 8 which thus leads toward and into the stem 3 when the fitting 4 is in its assembled position. The wall 7 is tapped at 9, and thereinto is threaded a grate 10 for the tobacco, which grate may be made of absorbent material or any other suitable substance. The grate 10 is provided with a series of perforations 11 surrounding the region of a chamber 12 to convey the smoke to the gutter portion 13, and it is preferably provided with a

central slotted lug 14 for applying a screw-driver for inserting or removing the grate. If the grate 10 is made of a brittle absorbent material it may, when worn, be removed for discarding by being broken up and the remnants thrown out, whereupon a new tablet may be rethreaded into position. Said depressed gutter portion 13 of fitting 4 serves as a passageway for the smoke and to intercept any objectionable solidified or viscous ingredients that may be distilled out of the tobacco during the smoking. The underside of the grate 10 is provided with an arched chamber 15 which surrounds the projection 6 and leads to the gutter 13 and opening 8. During use of the pipe, the smoke is conveyed from the bowl 2 through the perforations 11 of the grate 10, through the gutter 13 laterally upwardly through the chamber 15, and downwardly through the conduit 8 and into the stem 3. In the utilization of the pipe, the grate 10 absorbs the objectionable ingredients of the tobacco resting thereupon, and the same are further absorbed by the passage of the smoke through the perforations 11, underneath the grate 10, and through the arched chamber 15, while the objectionable distillates of the tobacco are simultaneously intercepted and caught by the gutter portion 13, so as to prevent entry thereof into the stem 3. After the grate 10 becomes worn, the same may be discarded and a new one replaced, and at any time convenient access may be had to the gutter 13 with any suitable implement for removing any solid or viscous matter that may be found therein.

Having thus described my invention, I claim:—

1. In a tobacco pipe, the combination with a bowl and stem, of a fitting wedged in said bowl having a floor, a central projection extending upwardly from said floor having an opening leading to said stem, an annular wall of said fitting surrounding said projection, said wall being tapped and a tablet of absorbent material adapted to thread into said tapped wall and having a chamber thereunder surrounding said projection, whereby the smoke will be directed downwardly through said tablet, upwardly into said chamber, and downwardly through said opening into said stem.

2. In a tobacco pipe, the combination with a bowl and stem, of a fitting wedged in said bowl having a floor, a central projection extending upwardly from said floor having an opening leading to said stem, an annular wall of said fitting surrounding said projection, said wall being tapped, and a grate adapted to thread into said tapped wall and having a chamber thereunder surrounding said projection.

JOSEPH PEDERY.
